GUSTAV BERNHARD PETSCHÉ, OF PHILADELPHIA, PENNSYLVANIA, ASSIGNOR TO SOUTHWARK FOUNDRY AND MACHINE COMPANY, OF PHILADELPHIA, PENNSYLVANIA, A CORPORATION OF PENNSYLVANIA.

STARTING DEVICE FOR GAS-ENGINES.

991,233.

Specification of Letters Patent.

Patented May 2, 1911.

Application filed February 25, 1907. Serial No. 359,291.

To all whom it may concern:

Be it known that I, GUSTAV B. PETSCHÉ, a subject of the Emperor of Germany, residing in the city and county of Philadelphia, 5 in the State of Pennsylvania, have invented a certain new and useful Improvement in Starting Devices for Gas-Engines, of which the following is a true and exact description, reference being had to the accompanying drawings, which form a part thereof.

My present invention relates to the starting of gas engines by compressed air or gas and is primarily designed for use in starting gas engines having four explosive chambers, 15 in each of which the operation is on the four cycle plan, and as so designed, my present invention comprises mechanism actuated by the valve gear controlling the valves of the engine in normal operation. The starting 20 mechanism thus actuated by the regular valve gear in starting admits compressed air or gas to each explosive chamber or working cylinder end, during the portion of the cycle carried out in said chamber or cylinder end 25 corresponding to the stroke of the piston therein which in regular operation would be the working stroke.

Thus considered, my present invention differs from that described and claimed by 30 my prior application, Serial Number 238,918, filed December 30, 1904, in important features of construction and arrangement of the starting mechanism and the manner in which it is actuated by the regular valve 35 gear, the object of my present invention being to simplify and improve upon the invention of my prior application.

While primarily designed for use with a gas engine of the character referred to above, 40 my invention comprises numerous novel features of construction and arrangement not necessarily limited to use with any particular type of engine.

The various features of novelty which 45 characterize my invention are pointed out with particularity in the claims annexed to and forming a part of this specification. For a better understanding of my invention, however, and the advantages obtained there 50 by, reference may be had to the accompanying drawings and descriptive matter in which I have illustrated somewhat diagrammatically, one of the forms in which my invention may be carried out.

In the drawings, Figure 1 is a semi-diagrammatic figure, showing my improved starting mechanism applied to gas engines having two double acting cylinders arranged in tandem. Fig. 2 is a transverse sectional elevation through one of the working cylinders, showing the regular inlet and outlet valves and actuating mechanism therefor, and also the starting valve mechanism. Fig. 3 is a sectional elevation of the pilot starting valve, and Fig. 4 is a sectional plan of the main starting valve taken on the line 4—4 of Fig. 2.

Referring to the drawings, A, A represent the working cylinders arranged in tandem, the pistons A¹ in the cylinders (not 70 shown in Fig. 1) being connected to each other by the piston rod B.

C¹, C², C³ and C⁴ represent the regular exhaust valve casings at the ends of the cylinders, each of the valve casings being connected by exhaust pipes D to the main exhaust pipe D¹.

The main outlet or exhaust valve E, one in each of the casings C¹, C², C³ and C⁴, and inlet valve mechanism F for each cylinder end are operated in any suitable manner so that the operation in each cylinder is carried out on the four cycle plan. In the engine shown the regular valve actuating mechanism is arranged so that the stems E¹, E², E³ 85 and E⁴, connected to the exhaust valves in the casings C¹, C², C³ and C⁴ respectively, open successively in regular order, and of course each one piston stroke before the opening of the corresponding inlet valve F. 90

In the form disclosed in Fig. 2 the four main inlet valves F, and the four main exhaust valves E are operated by two sets of cams G and G¹ which reciprocate in paths parallel to the cylinders A, A and are operated by cranks set ninety degrees apart on a shaft, rotating at half the speed of the main driving shaft of the engine. I have not herein specifically illustrated this mechanism as it forms no part of the present invention, but on the contrary is fully described and claimed in my co-pending application number 238,917, filed on the 30th day of December 1904.

To the valve casings C¹, C², C³ and C⁴ are 105 secured starting valve casings H¹, H², H³ and H⁴ respectively, each of which has an inlet passage or chamber, H⁵, and an outlet

passage or chamber, H^c . The inlet chamber H^5 of each valve is connected by a port H^7 to the pipe H^8 . The pipes H^8 are connected in turn to the supply pipe H which is the source of compressed air, and by the term compressed air I mean to include any fluid under pressure of the general character of compressed air. Similarly, each exhaust chamber H^6 is connected by a port H^9 to the corresponding exhaust pipe H^{10} , which may be open to the atmosphere or may be connected into the main exhaust pipe D^1 . Ports H^{11} and H^{12} lead from the admission and exhaust chambers H^5 and H^6 respectively, to the centrally located piston valve chamber H^{13} . A passage H^{14} leads from one end of the chamber H^{13} to the passage C^5 , connecting the corresponding cylinder end with the main exhaust port C^6 , controlled by the corresponding main exhaust valve E . It should be noted that the diameter of each valve E is less than the width of the corresponding passage C^5 . In consequence, the valves E , which extend into the passages C^5 , do not fill the latter and do permit air to pass to any combustion chamber from the corresponding starting valve port H^{14} when the corresponding valve E is on its seat.

In normal operation the passages H^{14} and C^5 are separated by the valve I , the stem I^1 of which carries the piston I^2 working in the chamber H^{15} of the starting valve casing. On the stem I is slidingly mounted the large piston I^3 working in the chamber H^{16} . A spring J , surrounding the stem I^1 , extends between the pistons I^2 and I^3 and normally holds them in the position shown in Fig. 4 in which they are fully separated and the valve I is on its seat. The piston I^3 has connected to it a guiding extension I^4 which works in the chamber H^{13} , and also the hollow piston valve I^5 , which moves from the position shown in Fig. 4 in which it closes the ports H^{11} to the position in which it opens these ports and closes the ports H^{12} .

The inlet chambers L^5 of the pilot valves L are supplied with compressed air when the starting mechanism is in operation, in any suitable manner as by connecting them through small pipes K to the ports H^{17} leading from the inlet chambers of the various starting valves. The outlet chamber L^6 of each pilot valve is connected by a pipe M to the port H^{18} , leading to the inner end of the chamber H^{16} in which the piston I^3 of the proper starting valve works. The chambers L^5 and L^6 of each pilot valve, are normally separated by a piston valve L^7 working in a cylinder L^8 , open at its lower end to the valve chamber L^5 , and having its interior connected with the valve chamber L^6 by a series of ports L^9 . The stem L^{10} of each pilot valve is adapted to engage an arm E^5 , carried by the stem of the corresponding main exhaust valve, and to be held by said

arm when the main exhaust valve is closed in the position shown in Fig. 3, in which the piston is below the ports L^9 and the chambers L^5 and L^6 are separated. When the arm E^5 is raised, however, as the main exhaust valve opens, the piston L^7 is moved by the air pressure beneath it to a position above the ports L^9 and communication is thus established between the chambers L^5 and L^6 . (See left hand end of Fig. 1). The arrangement is such that the pipe M from each pilot valve runs to the starting valve of the cylinder end in which in normal operation a working stroke would be carried out while the exhaust valve controlling the pilot valve is open. The inlet chamber H^5 of each starting valve is connected by a passage H^{19} and pipe H^{20} , to the outer end of the chamber H^{15} in which the piston I^2 works.

In starting the gas supply admitted to the cylinders by the valves F , in regular operation is cut off, and the pipes H^8 are supplied with compressed air or gas by the supply pipe H . The pressure of the compressed air thus admitted to the inlet chambers H^5 and H^{19} and transmitted therefrom through the ports H^{19} and pipe H^{20} to the outer ends of the various chambers H^{15} is sufficient to move the pistons I^2 to the right against the action of the springs J , and thus move all the valves I off their seats, whereby each cylinder end is in communication through the passage C^5 with the passage H^{14} .

In any position in which the engine may have stopped one of the main exhaust valves E is left open and the corresponding stem raised. (In Fig. 1 the extreme left end stem E^4 is raised.) In consequence the corresponding piston valve L^7 is moved by the air pressure in the chamber L^5 to connect the chambers L^5 and L^6 and pressure passes to the port H^{18} of the proper starting valve casing; viz., the casing H^1 when the parts are in the position shown in Fig. 1. This pressure acting on the inner side of the large piston I^3 moves it to the left against the action of the spring J , and closes the ports H^{12} of that starting valve and opens the ports H^{11} admitting compressed air to the corresponding cylinder end from the inlet chamber H^5 of the starting valve casing which chamber is in communication with the compressed air supply pipe H through pipe H^8 . The spring J is not sufficiently strong to move the piston I^2 outward against the action of the pressure acting on it, so that the valve I remains open. The pressure thus admitted to the cylinder end starts the engine in operation and at the end of a piston stroke the main exhaust valve which was open, is closed by the regular valve gear, whereupon the corresponding pilot valve is of course closed and the starting valve controlled by it returns to its original condition, a leadage port or ports L^{11} being provided to permit

the escape of air from the pilot valve chamber L⁶. When the starting valve returns to its original position the piston I³ closes ports H¹¹ and opens ports H¹², thus allowing the 5 air in the corresponding end of the working cylinder to escape through ports H¹² into the starting valve outlet chamber H⁶ and from thence into the outlet pipe H¹⁰. As one main 10 exhaust valve closes another opens thus allowing the pilot valve controlled by it to open and the operation thus described is repeated to admit pressure to another cylinder end and so on.

By the use of my invention the piping for 15 supplying compressed air to the cylinder ends to move the engine is simple and can be conveniently disposed, a matter of considerable importance, especially in large engines, where proper disposition of the ordinary starting devices is a troublesome matter. The pipes K and M connected to the pilot valves can be, of course, much smaller than the main pipes supplying the compressed air, and a suitable disposition of 25 these smaller pipes is easily obtained.

The starting mechanism can be applied in a very simple manner to the regular valve gear without necessitating any change in the operation or construction of the latter, except the addition of the arms E² or equivalent devices. While I prefer to operate the starting valves from the stems of the exhaust valves as shown, it will of course be understood that they may be operated from 35 other portions of the valve gear, or indeed, under some circumstances, it may be desirable to operate them from some other moving parts of the engine. It will, of course, be understood that certain features of my 40 invention may be employed without a corresponding use of others.

Usually in two or three revolutions of the engine shaft sufficient momentum is acquired by the fly-wheel to carry the engine along 45 and the starting mechanism is then cut out of service by the simple expedient of cutting off the supply of compressed air, and at the same time the regular supply of explosive mixture is connected to the engine, 50 which then operates in the regular manner.

Having now described my invention, what I claim as new and desire to secure by Letters Patent is:

1. In a gas engine having one or more 55 working chambers and a valve gear controlling the admission to and exhaust from each chamber in normal operation, starting mechanism including a starting valve casing for each chamber having a passage leading to 60 the corresponding working chamber and another passage and means for supplying compressed air to the last mentioned passage, a valve in said casing controlling communication between said passages, and fluid pressure actuating means for said valve, includ-

ing a pilot controlling valve, means actuated by the valve gear for controlling said pilot valve and a pipe controlled by said pilot valve and running from the pilot valve to the starting valve casing.

2. In a gas engine having a plurality of working chambers, starting valve casings, one connected to each working chamber, pipes supplying compressed air to the starting valve casings throughout the starting 75 operation, one connected to each of said casings, a starting valve in each starting valve casing and fluid pressure actuating mechanism for the starting valves including a pilot valve for each starting valve adjacent 80 to and operated by a moving part of the engine.

3. In a gas engine having a plurality of working chambers, a main exhaust valve casing for each chamber, said main exhaust 85 valve casings being arranged side by side, starting valve casings one attached to each main exhaust valve casing, pipes for supplying compressed air to the starting valve casings, one connected to each starting valve 90 casing, starting valves, one in each starting valve casing and fluid pressure actuating mechanism for the starting valves, including a pilot valve for each starting valve located adjacent to and operated by a moving part 95 of the engine.

4. In a four-cycle gas engine having one or more working chambers and a valve gear for controlling the admission to and exhaust from each chamber in normal operation, 100 starting mechanism comprising a starting valve for each chamber operating in starting to admit compressed air to said chamber during the piston stroke which in normal operation would be the working stroke, and to connect the chamber to exhaust during the other piston stroke, means for supplying each starting valve with compressed air and means for operating said valves including a pilot valve for each starting valve and 105 connections from the pilot valves to said valve gear.

5. In a four-cycle gas engine having one or more working chambers and a valve gear for controlling the admission to and exhaust from each chamber in regular operation, starting mechanism including a starting valve casing for each chamber having a supply passage or chamber and an exhaust chamber or passage connected to exhaust, means for supplying compressed air to said supply passage or chamber, a starting valve for each casing movable from a position in which it closes communication between the working chamber and the exhaust passage 115 to a position in which it closes communication between the working chamber and the supply passage, and means controlled by the valve gear for moving each of said starting valves so that each working chamber is 120 125 130

connected to the supply passage during the period corresponding to the working stroke, carried out in the chamber in regular operation and to exhaust at other times.

5 6. In a four-cycle gas engine having one or more working chambers, starting mechanism including a valve casing for each working chamber having a passage leading to said chamber, a supply chamber, and an 10 exhaust chamber connected to exhaust, and having the supply and exhaust chambers connected to said passage by inlet and exhaust ports respectively, means for supplying said supply chamber with compressed 15 air, a valve located in said passage for controlling the inlet and exhaust ports, and means for moving said valve in starting to open said inlet port during the piston stroke which in normal operation would be the 20 working stroke and to open the exhaust port during the strokes which in normal operation would be the exhaust, admission and compression strokes.

7. In a four-cycle gas engine having one 25 or more working chambers, starting mechanism including starting valve casings, one for each combustion chamber, each of said casings having a passage leading to the working chamber, a supply chamber and an 30 exhaust chamber connected to exhaust, and having said supply and exhaust chambers connected to said passage by ports, means for supplying compressed air to said supply chamber, a valve controlling said ports and 35 movable from a position in which it opens one port and closes the other to a position in which it closes the one and opens the other, yielding means tending to hold the valve at all times in one of said positions, and means 40 actuated by the movement of the engine for moving the valve at intervals into the other position.

8. In a gas engine having a plurality of working chambers, and a valve gear for controlling the admission to and exhaust from 45 said chambers in regular operation, starting mechanism including a valve casing for each working chamber, said casing having a passage connected to the working chamber, a 50 supply chamber connected to said passage by an inlet port, an exhaust chamber connected to exhaust and to said passage by an exhaust port, and a piston chamber, means for supplying compressed air to said supply 55 chamber, a valve controlling said ports and movable from a position in which it closes the inlet port and opens the exhaust port to a position in which it closes the exhaust port and opens the inlet port, yielding means 60 tending to hold the valve in one position, and means for moving the valve against the action of said yielding means to the other position, said means including a piston, a 65 pilot valve controlling communication between said piston chamber and said source

of compressed air and a connection from said valve gear for controlling said pilot valve.

9. In a gas engine having a plurality of working chambers, starting mechanism including starting valve casings one for each chamber, each starting valve casing having a valve chamber H^{13} , inlet and exhaust chambers H^5 and H^6 connected to the valve chamber by the ports H^{11} and H^{12} respectively, and also having the piston chambers H^{10} and H^{15} , means supplying one end of the latter chamber in starting with fluid under pressure, a starting valve mechanism for each starting valve casing, including a valve I controlling communication between the valve chamber and the corresponding working chamber, piston I^2 connected to the valve I, working in chamber H^{15} and arranged to open the valve I when the pressure is admitted to said end of the chamber H^{15} , piston I^3 working in chamber H^{16} , valve I^5 connected to piston I^3 and controlling ports H^{11} and H^{12} , and a spring J, normally holding piston I^3 in position in which valve I^5 closes port H^{11} and uncovers port H^{12} , and means actuated by the movements of the engine for intermittently admitting fluid under pressure to chamber H^{16} to move the valve I^5 through piston I^3 to uncover port H^{11} and close port H^{12} .

10. In a gas engine having a plurality of working chambers, starting mechanism including starting valve casings one for each chamber, each starting valve casing having a valve chamber H^{13} , inlet and exhaust chambers H^5 and H^6 connected to the valve chamber by the ports H^{11} and H^{12} respectively, and also having the piston chambers H^{10} and H^{15} , means supplying one end of the latter chamber in starting with fluid under pressure, a starting valve mechanism for each starting valve casing, including a valve I controlling communication between the valve chamber and the corresponding working chamber, piston I^2 connected to the valve I and working in chamber H^{15} and arranged to open the valve I when pressure is admitted to said end of the chamber H^{15} , piston I^3 working in chamber H^{16} , valve I^5 connected to piston I^3 and controlling ports H^{11} and H^{12} , and a spring J tending to hold pistons I^2 and I^3 in the positions in which the valve I is closed and the port H^{11} is covered and the port H^{12} is uncovered, and means actuated by the movements of the engine for intermittently admitting fluid under pressure to chamber H^{16} to move the valve I^5 through piston I^3 to uncover port H^{11} and close port H^{12} .

11. In a gas engine having a plurality of working chambers, starting mechanism including starting valve casings one for each chamber, each starting valve casing having

a valve chamber H^{13} , inlet and exhaust chambers H^e and H^o connected to the valve chamber by the ports H^{11} and H^{12} respectively, and also having the piston chambers H^{16} and H^{15} , means supplying one end of the latter chamber in starting with fluid under pressure, a starting valve mechanism for each starting valve casing, including a valve I controlling communication between the valve chamber and the corresponding working chamber, piston I^2 connected to the valve I and working in chamber H^{15} and arranged to open the valve I when pressure is admitted to said end of the chamber H^{15} , piston I^3 working in chamber H^{16} , valve I^6 connected to piston I^3 and controlling ports H^{11} and H^{12} , and a spring J , normally holding piston I^3 in position in which valve I^6 closes port H^{11} and uncovers port H^{12} , pilot valves L , one for each starting valve, each pilot valve having an inlet chamber supplied with fluid under pressure and an outlet chamber connected to the end of the chamber H^{16} , from which the piston I^3 moves to uncover the port H^{11} and cover the port H^{12} , and means supplied by the movement of the engine for intermittently actuating said pilot valves to connect their inlet and outlet sides.

12. In a gas engine having a plurality of working chambers a valve gear controlling the admission to and exhaust from the working chambers in normal operation, a starting valve for each working chamber, fluid pressure actuating mechanism therefor, including a pilot valve for each starting valve, each pilot valve comprising a casing having an inlet chamber supplied with fluid under pressure, an outlet chamber connected to the starting valve and a valve member movable from a position in which communica-

tion between the inlet and outlet chambers is closed to a position in which communication between said chambers is established and a connection between said valve chamber and the valve gear whereby the latter moves said valve member from one of said positions to the other.

13. In a gas engine having a plurality of working chambers and a valve gear for controlling the admission to and exhaust from said chambers in regular operation, a starting valve for each chamber and fluid pressure actuating mechanism therefor, including a pilot valve for each starting valve, said pilot valve having a casing with an inlet chamber supplied with fluid under pressure, and an outlet chamber, said chambers being connected by a passage, and a valve member controlling said passage and normally urged from the position in which communication between the chambers is closed to the position in which it is open by the fluid pressure in the inlet chamber, and a connection from said valve gear which normally holds said valve member in the position in which the passage is closed but intermittently allows the valve member to move to open said passage.

14. In an internal combustion engine having inlet and outlet valves and means for operating them, a starting valve, a compressed air supply, mechanism operated by compressed air for opening the starting valve and keeping it open, and independent means for regulating the admission and exhaust of compressed air through the starting valve.
